UNITED STATES PATENT OFFICE.

LOUIS PHILIPP COHEN, OF NEW YORK, N. Y.

FURNACE.

SPECIFICATION forming part of Letters Patent No. 783,614, dated February 28, 1905.

Application filed December 29, 1903. Serial No. 187,000.

To all whom it may concern:

Be it known that I, LOUIS PHILIPP COHEN, a citizen of the United States, and a resident of New York, in the county and State of New York, have invented new and useful Improvements in Furnaces, of which the following is a specification.

This invention relates more particularly to steam-boiler and other furnaces having inclined grates, a fuel-hopper above the grates, and means for feeding the fuel from the hopper upon the upper ends of the grates.

My invention has for its object to provide a simple, efficient, and satisfactory mechanical apparatus for shaking the grate with a view of maintaining a practically even layer of coal, breaking up the coat of silicate which is liable to be formed under the prevailing high temperature, and facilitating the movement of the coal over the grate.

In the accompanying drawings, consisting of two sheets, Figure 1 is a longitudinal sectional elevation of a furnace provided with my improvements. Fig. 2 is a fragmentary rear view of the front portion of the roof of the combustion-chamber in line 2 2, Fig. 1. Fig. 3 is a perspective view of one of the removable throat-plates. Fig. 4 is a side elevation of the driving-shaft and its chain-pulley. Fig. 5 is a fragmentary bottom view of the upper portion of the main grate, on an enlarged scale, viewed in the direction of the arrow 5. Fig. 6 is a transverse section in line 6 6, Fig. 1, looking rearward. Fig. 7 is a horizontal section taken above the shaft of the rock-arms in line 7 7, Fig. 1. Fig. 8 is an enlarged fragmentary front elevation of the movable cleaner-grate, the bars of the main grate appearing in section. Fig. 9 is a top plan view of the front portion of the roof of the combustion-chamber, the brackets being omitted. Fig. 10 is a side elevation of the mechanism for operating the rock-arms of the main grate.

Like letters of reference refer to like parts in the several figures.

A represents the side walls of the furnace; A', the front wall; A², the ash-pit, and A³ the combustion-chamber.

B represents the front portion of the roof

of the combustion-chamber, and B' the rear portion thereof.

C represents a hollow cross-beam which is arranged in front of the roof of the combustion-chamber and provided with air-openings 55 c in its lower side, through which the air is delivered into the upper portion of the combustion-chamber.

D represents the fuel-hopper, which is arranged above and in front of the hollow cross-beam C and preferably hinged or pivoted at the front, as shown at d.

The front portion B of the roof of the combustion-chamber is composed of fire-bricks b, which are arranged loosely side by side and 65 supported at the front by a rib or flange b', projecting rearwardly from the lower edge of the hollow beam C and at the rear by brackets B², having at their lower ends forwardly-projecting ribs or flanges b³. Each brick is 70 supported at its front side by a ledge b² upon the rib b' and at its rear side by the rib b³, which projects into a groove b⁴ in the rear side of the brick. The brackets are secured to the rear face of the upper rib b⁶ of the cross-beam 75 C. These bricks are suspended at their upper cold parts and are allowed to expand freely under the influence of the high temperature of the furnace. A sheet of asbestos is placed, preferably, in every joint, and the 80 whole row of bricks is pressed together by a screw b⁷, as represented in Fig. 9, or some other suitable device. The life of the bricks is thus increased, and the removal of them, if they are required to be replaced, is easily accomplished upon detaching the brackets. By 85 the action of these bricks the temperature of combustion is much increased, thereby improving the combustion, saving fuel, and improving the effect of the boiler. 90

E represents a rotating feed-roller whereby the fuel issuing from the hopper is propelled downwardly toward the grate. This feed-roller is arranged transversely underneath the hopper-outlet and consists of a sleeve e, which 95 is mounted on a transverse shaft e' and carries longitudinal ribs or wings e². A feed-throat is formed between the rear side of the feed-roller and the front of the hollow cross-beam C, through which throat the fuel passes from 100

the hopper down to the grate. The width of this throat can be changed by removable lining-plates F, as the thickness of the layer of fuel or the size of the fuel may require.

5 These throat-plates are supported by hooks f' on a ledge f'', formed on the front side of the hollow cross-beam C, so that upon swinging the feed-hopper forwardly on its hinge the plates can be removed and replaced by similar plates of greater or less thickness to contract or enlarge the throat.

10 The front portion of the feed-roller is inclosed in a semicylindrical casing G, having its upper edge adjacent to the front edge of the hopper-outlet. This roller rotates in such a direction that its wings sweep downwardly through the front portion of the feed-throat and upwardly through the casing. The feeding action of the feed-roller becomes effective 15 only when the fuel is shaken down, because the wings of the roller are just wide enough to take hold of the fuel to keep the throat filled up; but they are not so wide as to extend across the feed-throat. Hence when the outlet 20 of the throat is filled with fuel the wings carry the fuel around through the upwardly-increasing space of the casing without feeding the fuel downward.

25 The feed-roller shaft is journaled near its ends in bearings h, arranged in the side walls, and is provided at one end with a worm-wheel h', which is engaged by a worm h'', rotated by a driving mechanism of any suitable construction—for instance, a pulley h³ and belt h⁴.

30 I represents the top grate, which extends downwardly and forwardly from the lower portion of the feed-roller casing and which is of angular form in order to keep its spaces free for the passage of air.

35 K represents the main grate, which extends rearwardly from the lower end of the top grate in an inclined position. The main grate is composed of two series of grate-bars k' and k'', which alternate with each other and are pivoted or movably supported near their lower ends, so that their upper ends can be swung backwardly and forwardly or upwardly and downwardly in an oblique direction about the lower support as a pivot. For that purpose 40 these grate-bars are preferably provided near their lower ends with half-round sockets k³, by which they rest loosely upon a corresponding cross-bar k⁴. The main-grate bars are secured together to form two sets in which the 45 grate-bars alternate. The two sets can be moved up and down in opposite directions for shaking the grate, and they can be lowered together for giving access to the combustion-chamber. For these purposes the following 50 mechanism is provided.

L represents a supporting and agitating shaft arranged transversely in front of or below the upper portions of the main-grate bars and supporting the latter. This shaft is journaled near its ends in bearings l of any suit-

able construction, formed on the rear ends of rock-arms l'. The front ends of these rock-arms are secured to a transverse rock-shaft l'', which is journaled in bearings at or near the front wall of the furnace and provided 70 with a suitable operating mechanism—for instance, a segment l³, worm-shaft and worm l⁴ l⁵, and hand-wheel l⁶. Upon turning the rock-shaft in the proper direction to lower the supporting-shaft both sets of main-grate 75 bars are swung downwardly, as indicated by the dotted lines in Fig. 1, thereby affording access to the combustion-chamber for preparing the grate for starting the fire or for pushing the fire back for banking.

80 The two sets of grate-bars can be moved up and down a short distance alternately or in opposite directions for loosening or detaching the layer of coal, breaking up the layer of silicate formed by the molten ashes produced 85 by the very high temperature in the furnace, and for shaking down the ashes. This alternating rocking movement is imparted to the two sets of grate-bars as follows: The main-grate bars k' k'' are provided near their upper 90 ends with downwardly-extending lugs m and n, respectively, which are connected by transverse bars m' and n', respectively, so that all bars of each series are moved simultaneously. O O' represent eccentrics or cams secured to the 95 supporting and agitating shaft L, near the ends thereof, and supporting, respectively, a pair of the rocking grate-bars k' and k''. The two pairs of cams are arranged out of line, as shown in Figs. 1 and 6, or otherwise, so that 100 upon rotating the agitating-shaft L they cause the two sets of bars to move in opposite directions forwardly and backwardly.

P represents a short driving-shaft which is arranged to be coupled with the agitating-shaft L when the latter is in its normal operative position. This driving-shaft is arranged axially in line with the operative position of the agitating-shaft and journaled in a bearing p, arranged in one of the side walls of the 105 furnace. This driving-shaft is driven by any suitable mechanism—for instance, by a sprocket-wheel p', operated by a chain belt p² from a sprocket-wheel p³, mounted on the feed-roller.

110 Q represents a coupling rod or pin whereby the driving-shaft P and the agitating-shaft L are coupled for driving the latter. This rod is flat-sided and is inserted in a correspondingly-shaped opening q' and socket q'', formed 115 lengthwise in the driving-shaft P and the adjacent end of the agitating-shaft L, respectively. Upon withdrawing the coupling-rod from the agitating-shaft by means of the handle q³, formed on the outer end of the rod, 120 the agitating-shaft is uncoupled and free to be swung down for lowering both sets of the main-grate bars. The inner end of the coupling-rod is preferably tapered to facilitate its 125 entrance into the socket of the agitating-shaft. 130

R represents the lower or slag grate, which is arranged in a nearly-horizontal position at a short distance below the main grate and which extends rearwardly therefrom for receiving ashes and clinkers. This grate is supported at its front and rear ends by cross-bars $r r'$, respectively, and is separated from the lower end of the main grate by a cleaning opening or space r^2 , through which the ashes and slags are removed.

S represents a movable cleaner-grate which closes the cleaning-opening between the main grate and the slag-grate and which can be swung out of the way forwardly and downwardly, as indicated by dotted lines in Fig. 1, to permit the ashes and slags to be removed from the slag-grate. The cleaner-grate is pivoted at its lower end to forwardly-projecting lugs s' , secured to the cross-bar r , and stands at an angle of about sixty degrees to the horizon when in its normal position. The cleaner-grate is composed of thin bars arranged to project with their upper ends into the spaces between the lower ends of the main-grate bars, which latter are at their lower ends so thin that the bars of the cleaner-grate can enter into the spaces between them, as represented in Fig. 8. This prevents the formation of an objectionable opening between the main-grate bars and the upper end of the cleaner-grate when the main grate is swung down for giving access to the combustion-chamber, as represented in dotted lines in Fig. 1.

T is a shifting-rod by which the cleaner-grate is opened and closed and which is pivoted at its rear end to an arm t , projecting forwardly from the channel-iron t' , to which the grate-bars are secured. This shifting-rod extends to the front wall of the furnace and is held out of the way by hanging its handle t^2 on a bracket t' .

I claim as my invention—

1. The combination of two series of inclined grate-bars, the bars of one series alternating with the bars of the other series, a cross-piece by which the bars of each series are rigidly connected, a stationary cross-bar upon which the bars are supported near their lower ends and on which said bars can oscillate, a transverse agitating-shaft arranged underneath the upper portions of the bars and provided with two sets of cams which project in opposite directions and each of which supports a series of said bars, and mechanism for rotating said shaft, substantially as set forth.

2. The combination of a grate pivoted near one end, an agitating-shaft arranged underneath the grate near the other end thereof and provided with cams on which the grate rests, means for rotating said shaft, and vertically-movable supports on which said shaft is journaled and by which said shaft and the grate can be raised and lowered together, substantially as set forth.

3. The combination of an inclined grate, a 65 stationary support on which the grate is supported near its lower end, an agitating-shaft arranged underneath the upper portion of the grate and provided with cams on which the grate rests, means for rotating said shaft, and 70 rock-arms on which said shaft is journaled and which are movable up and down, substantially as set forth.

4. The combination of two series of grate-bars, the bars of one series alternating with 75 the bars of the other series, a stationary support on which the bars are supported and on which said bars can oscillate, a transverse agitating-shaft arranged underneath the grate-bars at a distance from said stationary support 80 and provided with two sets of cams which project in opposite directions and each of which supports a series of said bars, means for rotating said shaft to oscillate the two series of bars in opposite directions, and rock-arms in 85 which said shaft is journaled and which are movable up and down for raising or lowering said shaft and both sets of bars, substantially as set forth.

5. The combination of a movable grate, an 90 agitating-shaft engaging the same and mounted in movable supports, a driving-shaft arranged in line with the operative position of said agitating-shaft, and a coupling device for connecting said agitating-shaft with said driving-shaft or disconnecting it therefrom, substantially as set forth.

6. The combination of a movable grate, an agitating-shaft engaging the same and mounted in movable supports, rock-arms in which 100 said shaft is journaled and which can be swung down for lowering the grate out of its normal position, a driving-shaft in line with the operative position of said agitating-shaft, and a coupling device for connecting said agitating-shaft with said driving-shaft or disconnecting it therefrom, substantially as set forth.

7. The combination of an inclined grate pivotally supported near its lower end, an agitating-shaft arranged below the grate near its 110 upper end, rock-arms in which said shaft is journaled, a driving-shaft arranged in line with said agitating-shaft in the operative position of the latter, and a releasable coupling connecting the driving-shaft with the agitating-shaft, substantially as set forth.

8. The combination of a grate composed of two sets of grate-bars, each set being movably supported and capable of independent as well as simultaneous movement, a shaft provided with agitating devices which operate upon each set of bars, a movable support for said shaft, a driving-shaft, and a coupling device which connects the driving-shaft with the agitating-shaft in the operative position of the latter, and upon being uncoupled, permits the support and the grate to be lowered, substantially as set forth.

9. The combination of a movable grate, an agitating-shaft arranged below the same having a socket in its end, agitating-cams arranged on said shaft, a movable support for said shaft, a hollow driving-shaft arranged in line with the operative position of said agitating-shaft, and a coupling-pin adapted to be inserted in said hollow driving-shaft and

the socket of said agitating-shaft, substantially as set forth.

Witness my hand this 21st day of December, 1903.

LOUIS PHILIPP COHEN.
